TABLE BASE

Keith N. Muller, 73 Balmoral Ave., Toronto 7, Ontario,
Canada, and Michael M. Stewart, 1 Laurier Ave.,
Toronto 5, Ontario, Canada

Filed Feb. 24, 1969, Ser. No. 15,887

Term of patent 14 years

Int. Cl. D6—01

U.S. Cl. D33—14

FIG. 1

FIG. 2

FIG. 1 is a perspective view of the table base looking toward a front corner thereof; and

FIG. 2 is a side elevational view of one of the two identical sides.

We claim:

The ornamental design for a table base, as shown.
